(57) **CLAIM**

The ornamental design for a “mounting device”, as shown.

DESCRIPTION

FIG. 1 is a perspective view of a “mounting device” showing my new design;

FIG. 2 is a front view thereof;

FIG. 3 is a rear view thereof;

FIG. 4 is a side view thereof, the opposite side being identical thereto;

FIG. 5 is a top plan view thereof;

FIG. 6 is a bottom plan view thereof; and,

FIG. 7 is a perspective view showing the “mounting device” in a folded configuration.
